Original application July 6, 1937, Serial No.
152,076. Divided and this application July 12,
1940, Serial No. 345,031

9 Claims. (Cl. 93—93)

This invention relates to the stacking of articles having substantially the shape of a parallelopipedon and may be used in the stacking of box heads, boxes, trays, or other similar articles.

This is a divisional application, the subject matter of which has been carved out of the pending application of Hale Paxton and Gerald C. Paxton, Serial No. 152,076, filed July 6, 1937, on Machine for the manufacture of box parts, now Patent No. 2,243,919, dated June 3, 1941.

It is an object of this invention to provide a stacking device for stacking articles of the type aforesaid to which a series of the articles to be stacked may be fed, and which will form a stack 15 of said articles and release the same for discharge from the device when the stack reaches a given size.

It is a further object of this invention to provide in such a box stacking device a novel means 20 for predetermining the size of the stack to be formed therein.

The manner of accomplishing the foregoing objects as well as further objects and advantages will be made manifest in the following description taken in connection with the following drawings, in which:

Fig. 1 is a front elevational view of a machine for the manufacture of box parts which includes therein a preferred embodiment of the present invention.

Fig. 2 is an enlarged plan view of said machine.

Fig. 3 is a longitudinal sectional view taken on the line 3—3 of Fig. 2 and illustrates the stacking device of said machine in the act of receiving an article to be stacked.

Fig. 4 is a fragmentary transverse sectional view taken on the line 4—4 of Fig. 3.

Fig. 5 is a view similar to Fig. 3 and illustrates the stacking device of said machine in the act of incorporating an article just received with the stack being formed therein.

Fig. 6 is a fragmentary view similar to Fig. 5 illustrating the manner in which the stacking device of said machine operates to cause the discharge of a stack after the latter has been formed in said device.

Fig. 7 is a fragmentary sectional view taken on the line 7—7 of Fig. 2 and illustrating the novel stack size determining mechanism of the stacking device of this invention.

Fig. 8 is a vertical sectional view taken on the line 8—8 of Fig. 7 and showing the stack sup-

porting fingers in their stack supporting positions.

Fig. 9 is a view similar to Fig. 7 and illustrates the manner in which the stack size determining mechanism is operated.

Fig. 10 is a view similar to Fig. 8 and illustrates the stack supporting fingers withdrawn from stack supporting position to permit the discharge of a stack from the stacking device.

Fig. 11 is a view similar to Fig. 10 and illustrates a stack being lowered between the stack supporting fingers when the latter are retracted from stack supporting position.

Fig. 12 is a fragmentary detail view comprising a horizontal section taken on the line 12—12 of Fig. 7.

Referring specifically to the drawings, it is to be noted that the preferred embodiment of the stacking device of this invention as therein disclosed is included in a box head sawing machine 20. This machine includes a frame 21, a box head runway and magazine means 22, a stack storage conveyor 23, a power mechanism 24, a feed mechanism 25, a saw mechanism 27 and a stacking mechanism 28.

The frame 21

The frame 21 preferably includes four legs 35, two of which carry fixed axle wheels 36, and two of which carry casters 37. The legs 35 are united at their upper ends by a rectangular angle iron head frame 38 and at their lower ends by a base frame 39. Mounted on top of head frame 38 is a top plate 40. This top plate is provided with openings 41, 42, 43, and 46. The frame 21 also has vertical members 50 which carry bearings 52.

The box head runway and magazine means 22

Rigidly secured to the upper face of the top plate 40 is an angle iron member 60 (which runs practically the full length of the top plate) and angle iron members 61, 62, and 63 which are disposed in alignment with each other and uniformly spaced from the angle iron 60 to cooperate therewith to form a box head guide runway 64. Mounted on the table top 40 just within the angle iron members 60, 61, and 62, and terminating at the plate opening 43 are box head supporting rails 65. Mounted on the angle irons 60 and 61 is a box head feed magazine 70 which includes upright flat bars 71 and 72 and upright angle iron bars 73 and 74, these bars all being secured at their lower ends to the angle iron members 60 and 61. Mounted on these upright bars are mag-

azine walls 78 and 79, the upper ends of these walls being spaced by spacers 80. The wall 79 at the left hand or open end of the magazine 70 is flared, as indicated in Fig. 2, and the corresponding end of the wall 78 is provided with a flared latchgate 81 which is yieldably biased inwardly into box head trapping position by a leaf spring 82 mounted on the upright bar 71. As clearly shown in Figs. 3 and 5, the inwardly extending flanges 85 of the angle iron bars 73 and 74 extend into the path of the box heads in the magazine 70 to prevent the feeding of any of these heads from the magazine 70 except that disposed in lowermost position and resting directly on the rails 65.

Mounted on the angle iron 61 is a limit switch 86 having a finger 87 which is yieldably pressed inwardly into the magazine 70 into the position in which it is shown in Fig. 2, in a manner well known in the art, and when so positioned the circuit of the switch 86 is open. The switch 86 is so made, however, that when box heads are placed in the magazine 70, as shown in Fig. 4, so that two or more heads are disposed at the bottom of the magazine, the finger 87 is held outwardly by these heads, thus maintaining the circuit of the switch 86 closed.

That portion of the runway 64 which is disposed in the middle of the machine is where the box heads are positioned in what may be referred to as a "processing position" as it is in this position in which each box head is processed in the machine. As shown in Figs. 1 and 2, the angle iron 62 is provided with sloping slots 90 and the angle iron 60 is provided with a sloping slot 91, these slots all sloping downwardly toward magazine 70 and at the same angle. Mounted in the slots 90 and 91 by pins 92 and 93 is a saw guard and head gripping member 95, the pin 93 being secured to the member 95 by a bar 96 which is slidably in a suitable opening provided in the member 95 and adjustably secured thereto by a set screw 97. As indicated in Fig. 3, the left hand end of the member 95 is provided with an upwardly inclined guide face 98, the purpose of which will be made clear hereinafter. As shown in Fig. 2, the member 95 has a saw guard 99 provided thereon which is disposed directly over and in alignment with the opening 42 in the frame top plate 40.

At points opposite the processing position in the center of the machine previously referred to, the angle iron 60 is provided with guide bars 110 which are preferably welded to this angle iron member, the latter also having slots 111 formed in its upright flange opposite these bars. Disposed to slide against bars 110 and extend through the slots 111 so as to overlie the adjacent runway rail 65, is a pair of nailng anvils 112 which are yieldably held in engagement with the left ends of the slots 111 by coil springs 113. The inner edges of the anvils 112 are for the most part flat and parallel with the rails 65, but their leftward-most portions are beveled as shown in Fig. 2.

Mounted on the right hand end of the angle iron 60 and on the angle iron 63 is a stacker magazine 120 which is disposed directly over the opening 43 in the frame top plate 40 and includes upright flat bars 121 and upright angle iron bars 122 and 123 upon which magazine walls 124 are supported.

The walls and the upper ends of the bars 121, 122, and 123 are rigidly spaced by spacers 125.

Pivottally mounted on a vertical axis on the angle iron 63 is a stack stop 130 which is yieldably

held by spring 131 into a position as shown in Fig. 2 in front of a stack of heads disposed in the magazine 120.

The stack storage conveyor 23

This conveyor is preferably of the ordinary gravity type and includes an inclined gravity conveyor section 135 which is secured to the right hand end of the head frame 38 and is braced from beneath by a brace 136 connected to the base frame 39. At the end of the conveyor 135 is a stop 137.

The power mechanism 24

This mechanism includes an electric drive motor 140 mounted on the base frame 39, said motor preferably having incorporated therewith a reduction gearing on which is provided a pinion sprocket 141.

Journalled in the bearings 52 is a crank shaft 142 having a crank 143 on its rear end and which has fixed thereon in alignment with pinion 141 a master sprocket 145, the latter being connected to said pinion by a chain 146.

The box head feed mechanism 25

Secured to the bottom of the frame top plate 40, on opposite sides of the opening 41 therein, is a pair of guide bars 170 which, as shown in Figs. 2 and 4, slidably support a feed slide block 171. The block 171 has openings 172 and 173, in the first of which is pivotally mounted the rear end of an arm 174 having a feed dog 175 at its front end which extends up into opening 173. The arm 174 has a limited degree of movement relative to the slide block 171, by virtue of a pin 176 on this block extending into a slot 177 on this arm. The arm 174 is pivotally connected by links 178 to the upper end of a power lever 179, the lower end of which is pivotally mounted on a shaft 180 provided on the base frame 39 of the machine. The links 178 extend leftward beyond their pivotal connection with the lever 179 and are connected by a contractile spring 181 to the lever 179 to continually urge the arm 174 into its upwardmost position in which the dog 175 extends above the upper surface of the box head guide rails 65.

The lever 179 has a pin 182 which extends through a slot 183 in a bifurcated head 184 of a pitman 185 having a lower forked end 186 which is connected to the crank pin 187 of the crank 143, as shown in Fig. 3, (and as will be presently described), so that as this crank 143 rotates the lever 179 is swung back and forth causing a reciprocation of the sliding head 171 from one end of the magazine 70 to the other for the purpose of feeding box heads from the lower end of this magazine.

The saw mechanism 27

This mechanism has a rockable base 210 which is mounted on a shaft 211, the opposite ends of which are journalled in suitable bearings 212 provided on the frame 21. The base 210 supports an electric motor 213 and has a bearing 214 in which is journalled a saw shaft 215 having a pulley 216 which is directly connected by V-belts 217 to a pulley 218 mounted on the shaft of the motor 213. To the opposite end of the shaft 215 is fixed a circular saw 220 which lies in the vertical plane of the longitudinal axis of the opening 42 in the top plate 40 and the corresponding opening provided in the saw guard 99. The end of the bearing 214 adjacent the saw 220 provides an outer bearing surface which

pivotedly receives the upper end of a pitman 221, the lower end of which pivotally connects with crank 143 and is provided with a bearing ear 222 to which the bifurcated end 186 of the pitman 185 pivotally connects. It is thus seen that rotation of the shaft 142 reciprocates the saw 220 up and down between its lower position as substantially shown in Fig. 3 and its uppermost position as shown in Fig. 5.

The stacking mechanism 28

Provided on the saw mechanism base 210 is a lug 230 having a bolt 231 which is disposed in a slot 232 formed in a link 233. The upper end of the link 233 is pivoted at 234 to a pair of arms 235 on a shaft 236, the opposite ends of the latter journaling in bearings 237 provided on the frame. Disposed parallel with the shaft 236 and having its opposite ends journalled in bearings 240 provided on the frame is a similar shaft 241 having a pair of arms 242. Resting in its lowermost position on the shafts 236 and 241 and disposed on the longitudinal axis of the stacking magazine 120 is a stacking bar 243 to which the extremities of the arms 235 and 242 are pivotally connected by shafts 246 and 247. Mounted on opposite ends of the shafts 246 and 247 are stacking rollers 248. Another pair of similar rollers 249 are pivotally mounted in the same plane on a shaft 250 which is provided on the bar 243 in between the shafts 246 and 247.

Connected at its opposite ends to the saw mechanism base 210 and to the bar 243 is a contractile spring 251 which tends to yieldably maintain this bar in its lowermost position resting on the shafts 246 and 247.

Referring now to Figs. 7 to 12 inclusive, it is to be noted that shaft 236 extends forwardly through the forwardmost bearing 231, where it carries freely rotatable thereon a ratchet gear 260 having a series of semi-circular recesses 261 formed in its periphery. Gear 260 has a cam lug 262 provided on its rear face, as shown in Figs. 8, 10, and 11.

Fixed upon the forward extremity of the shaft 236 is an arm 263 which, with the gear 260, extends upwardly through opening 46 in the top plate 40 and into a hood 264 mounted on the top plate over this opening.

Provided on the upper end of the arm 263 is a dog 265 carrying a pin 266 which extends out through an opening 267 in the side of the hood 264, the lower surface of this opening being shaped to permit the pin 266 to drop downwardly into one of the recesses 261 in the periphery of the gear wheel 260 and rotate this wheel a given distance when the arm 263 rocks with the shaft 236.

Pivotedly mounted on the hood 264 and spring-biased downwardly is a detent dog 268 having a pin 269 which tends to rest at all times in one of the recesses 261, excepting when the ratchet gear 260 is being rotated by the pin 266.

Journalled at their ends in suitable bearing holes provided in the bearing blocks 237 and 240, are a pair of shafts 275 and 276, these having latch fingers 277 and 278, respectively, which extend upwardly from these shafts through suitable openings 279 in the angle irons 60 and 63 and inwardly through openings 280 in said angle irons, as shown in Fig. 8.

Provided on the magazine walls 124 and bearing against an opposite pair of the fingers 277 and 278 are leaf springs 281 for yieldably hold-

ing the fingers 277 and 278 in their inwardmost positions.

Shaft 275 has a short arm 282 extending downwardly therefrom adjacent the shaft 236, and a link 283, which is also adjacent the shaft 236, pivotally connects to arm 282 and to the finger 278 in alignment therewith as shown in Fig. 8. The forward end of the link 283 extends to a point close to the rear face of the ratchet gear wheel 261 and is there provided with a roller 284 which lies in the path of the cam lug 262 provided on this ratchet gear. When the ratchet gear 261 is rotated as by engagement of the pin 266 therewith, so as to bring the lug 262 into engagement with the roller 284, this results in the link 283 being swung rearwardly, thus rocking the shafts 275 and 276 and swinging the fingers 277 and 278 outwardly from within the magazine 120, as shown in Fig. 10.

Operation

The operation of the sawing machine 20 is as follows:

The magazine 70 is first furnished with a supply of blank box heads H so as to substantially fill this magazine, the lowermost heads in the magazine engaging the finger 87 of the switch 86, as shown in Fig. 4, to close this switch. As this switch is included in the wiring circuits of the motors 140 and 213, these motors may now be energized by turning on the switch controlling the supply of electricity thereto. When this takes place, the saw wheel 220, of course, is set in motion and rapidly rotated in the direction of the arrow 285 (see Figs. 3 and 5). At the same time, the shaft 142 is being rotated by the motor 140 in the direction of the arrow 286.

With the first rotation of the shaft 142, the feed dog 175 is caused to engage the lowermost blank box head H in the magazine 70 to feed this along the runway 64 into processing position. In this movement the head H engages the cam face 98 of the member 95, thereby shifting the latter slightly to the right, the slots 90 and 91 thereby causing this member to be raised slightly to admit this head H therebeneath. At the same time the movement of the head H along the runway 64 brings the rear edge of this head into engagement with the gripping wedges 112, so as to shift these slightly to the right, thereby making room for this head to move past them, though in close sliding contact with these wedges.

As the feeding movement of this head H into processing position is thus completed, the crank 143 swings upwardly the whirling circular saw 220 which, owing to the direction of its rotation, tends to return this head H from the position in which it is first contacted back toward the magazine 70 from which it came. Owing to the inclination of the slots 90 and 91, however, this tendency results in the member 95 binding said head H downwardly against the rail 65 on which the head is resting. At the same time this occurs, the tendency of this head H to return toward the magazine 70 under the impulse of the saw 220 causes a frictional engagement of this head with the wedges 112, thereby causing the latter to bind the head against the angle iron 62 and prevent any motion of the head in response to the rotating saw 220. Each head H, when it is fed into processing position and immediately thereafter engaged by the rising and rotating saw 220, is thus rigidly locked against returning toward the magazine 70 from which it came.

Following the processing of a given box head

H in the manner above described, the saw 220 returns downwardly with the downward swing of the crank 143 and another cycle of operations is commenced by the feeding of a fresh blank into processing position by another rightward movement of the dog 175. As the new blank is thus fed from the magazine 70 into processing position, it expels from this position the blank head just processed and the completion of the feeding of the second blank leaves the first one disposed within the stacking magazine 120. Rightward movement of this finished head is halted by its engaging the spring stop 130, the finished head now resting upon rollers 248 and 249 with the latter in their lower position, as shown in Fig. 3.

As the saw mechanism 27 is swung upward from the position in which it is shown in Fig. 3, to slot the second blank, the bolt 231 travels along the slot 232 of the link 233 and, having reached the upper end of this slot, starts to lift on the arms 235. This results in rocking the shafts 236 and 241 and lifting upwardly the rollers 248 and 249 and the finished head supported thereon.

As the rollers 248 and 249 rise, they lift the box head resting thereon against the fingers 271 and 278 and cam fingers apart permitting this box head to rise above the normal position of these fingers, whereupon the springs 281 shift said fingers back into the positions in which they are shown in Fig. 11. As the saw mechanism 27 descends at the conclusion of the processing of the second blank hereinabove discussed, gravity, assisted by the spring 251, will pull the bar 243 downward until it rests upon the shafts 236 and 241, thereby rocking the latter and returning the arms 235 and rollers 248 and 249 back into their lowermost positions in which they are shown in Fig. 3.

The first box head is now left resting on the upper ends of fingers 271 and 278 as shown in Fig. 8. As the operation of the machine 20 is continued and the successive box heads H are processed, fed into the stacking magazine, and lifted upwardly by the stacker mechanism 28, these heads accumulate above the fingers 271 and 278 to form a stack.

When the machine 20 is started, the ratchet wheel 261 is preferably adjusted so that the cam lug 262 is disposed just beneath the roller 284. The arm 263 is so fixed on the end of the shaft 236 that with each cycle of operation of the machine the pin 266 engages one of the recesses 261 in the ratchet gear 260 and rotates this gear exactly the space between adjacent recesses 261. As there are twenty-five recesses 261 about the periphery of the gear 260, it is thus seen that a stack of twenty-five heads H will have been processed and accumulated in the stacker magazine 120 before the gear 260 will have rotated sufficiently to bring the cam lug 262 to the position in which it is shown in Figs. 10 and 11 where it will engage the roller 284 and shift the fingers 271 and 278 outwardly. As this happens at a time when the rollers 248 and 249 are disposed upwardly so as to support the stack on the rollers, the return downward of these rollers as the saw mechanism is lowered does not leave the stack resting on the fingers 271 and 278 as was previously the case, but allows the stack to be carried downwardly on these rollers so that the lowermost box head in the stack is directly in line with the head just processed and which is about to be ejected into the stacker magazine. Being thus in the path of the incoming manufactured head, 75

the stack is expelled from the stacking magazine by said head as the latter moves into the stacking magazine, the spring stop 130 yielding to permit the stack to pass. When thus expelled, 5 the stack travels along the idle roller conveyor section 135 of the stack accumulating conveyor 23 and comes to rest against the end stop 137.

From the foregoing description, it is seen that after the machine 20 is once started, the only 10 thing that is necessary to do in order for the processing operation of the machine 20 to continue indefinitely without halting is to keep the feed magazine 70 supplied with blank box heads, and to keep the accumulating conveyor 23 from 15 becoming congested with stacks of processed heads. It is to be noted, however, that in the event that a supply of blank box heads is not maintained in the feed magazine 70, the finger 81 of the switch 86 will be automatically released and permitted to spring upwardly, thereby breaking the circuit of the switch and shutting off the 20 motors 140 and 213.

I claim:

1. In combination: means for feeding a series 25 of box parts in edge-to-edge relation along a given path; means to form a stack of said box parts in a given space above said path by lifting each of said box parts upwardly from said path into said space before the next successive box part is fed along said path beneath said space; releasable means for supporting said parts as so elevated; and means for releasing said stack from said supporting means when said stack reaches a predetermined size and permitting said stack 30 to be discharged from said space along said path by the continued feeding of said box parts.

2. In combination: means for feeding a series 40 of box parts in edge-to-edge relation along a given path; means to form a stack of said box parts in a given space above said path by lifting said box parts successively upwardly from said path, said means including yieldable dogs adapted to yield when each such part is moved upwardly and then shift into position beneath the 45 stack to support the latter; and means responsive to a predetermined number of operations of said stack forming means to retract said dogs thereby causing said stack to be lowered with a downward movement of said stack forming means and ejected from said space by an incoming 50 box part.

3. In a stacking device, the combination of: 55 means for elevating a series of articles, one at a time, along a given vertical path, to form a stack; means for supporting said stack as it is formed; and means operative upon said stack reaching a given size, to lower said stack along said path to substantially the same level from which said individual articles were elevated, to facilitate the delivery of said stack from said 60 stacking device.

4. In an article stacking device, the combination 65 of: means adapted to receive a series of articles, one at a time, at a given level, and elevate said articles in sequence as received to form a stack of said articles in a given vertical path; means applied to the lowermost article of said stack for supporting said stack as it is formed; and means operative, upon said stack reaching a predetermined size, for relaxing said stack 70 supporting means to permit said stack to ride downwardly on said elevating means to substantially the aforesaid level to facilitate the discharge of said stack from said device.

5. In a stacking device, the combination of:

means for elevating a series of articles, one at a time, along a given vertical path, to form a stack; means for supporting said stack as it is formed; means operative, when said stack reaches a predetermined size, to lower said stack along said path through said stack supporting means to facilitate the delivery of said stack from said device.

6. In a stacking device, the combination of: means for feeding a series of articles along a given level; elevating means operating in a given vertical path to receive said articles on said level and elevate said articles in sequence as they arrive in said path; means for receiving and supporting each article elevated by said elevator when said elevator returns downwardly after elevating said article; and means operative, when said stack reaches a given size, to withdraw said article supporting means from supporting relation with the lowermost article of said stack, to permit said stack to return downwardly on said elevator to facilitate the discharge of said stack from said stacker with the lowermost article of said stack substantially on said level.

7. In a stacking device, the combination of: means for feeding a series of articles along a given level; means for forming a stack of said articles in a given vertical path, into which said articles are fed by the aforesaid means; and means for releasing said stack and causing said stack to be returned to said level when said stack has reached a predetermined size, to permit said stack to be fed from said path by the feeding of the next article in said series into said path.

8. In combination: means for feeding a series of box parts or the like in edge-to-edge relation along a given path and into a given position therein; yieldable stop means for stopping the foremost box part in said position; idle rollers for supporting parts in said position; means for elevating each of said parts from said position into a given space above said path to form a stack of said parts in said space, said elevation occurring prior to the feeding of the next part into said position; releasable means for retaining said parts so elevated; and means for releasing said stack from said releasable means when said stack reaches a predetermined size, and permitting said stack to rest on said rollers in said path whereby said stack is discharged from the machine by the next part fed into said position.

9. In combination: means for feeding a series of box parts or the like successively to a given position; elevating means operating through said position to lift said box parts successively into the space thereabove; means for supporting each of said parts in said space when said part has been so elevated and thus forming a stack in said space; and means adjustable to predetermine the number of parts to be contained in said stack and rendering said supporting means inoperative to support the parts in said stack when said number of parts has been reached, thereby depositing said stack on said elevating means and facilitating the discharge of said stack from over said elevating means.

GERALD C. PAXTON.
